UNITED STATES PATENT OFFICE.

FRANK THORNTON, JR., OF PITTSBURGH, PENNSYLVANIA, ASSIGNOR TO WESTINGHOUSE ELECTRIC AND MANUFACTURING COMPANY, A CORPORATION OF PENNSYLVANIA.

TERMINAL DEVICE FOR ELECTRIC APPLIANCES.

1,308,127.

Specification of Letters Patent.

Patented July 1, 1919.

Application filed November 7, 1916. Serial No. 129,964.

To all whom it may concern:

Be it known that I, FRANK THORNTON, Jr., a citizen of the United States, and a resident of Pittsburgh, in the county of Allegheny and State of Pennsylvania, have invented a new and useful Improvement in Terminal Devices for Electrical Appliances, of which the following is a specification.

My invention relates to electrical appliances in which current-consuming circuits are to be connected in different combinations, and it has special relation to electric heating apparatus in which different degrees of heat are obtained by variously connecting the heating coils.

The object of my invention is to provide a terminal arrangement for apparatus of the above-indicated character by means of which several different combinations of conductors may be readily obtained, and by which, when applied to electric heating apparatus, three degrees of heat; viz., high, medium and low, may readily be obtained by connecting two circuits either in parallel, in series, or singly.

According to my invention, I make use of a terminal receptacle having four contact members connected in pairs to opposite sides of the supply circuit and I arrange the terminal contact members of the heating device in the manner shown in the accompanying drawing, in which:

Figure 1 is a side elevational view of an electrically heated grill provided with a terminal device constructed in accordance with my invention. Fig. 2 is a fragmentary plan view of a portion of the structure shown in Fig. 1. Fig. 3 is an end elevational view of the receptacle shown in Fig. 2. Fig. 4 is a diagrammatic view showing the arrangement of the circuits in the device of Fig. 1, and Fig. 5 is a diagrammatic view showing the manner in which the contact members of the receptacle are connected to the supply circuit.

My invention is here illustrated as applied to an electrically heated grill comprising a frame 1 supported upon legs 2 and provided with a terminal device 3. The terminal device 3 comprises a set of five contact pins 4, 5, 6, 7 and 8, four of these five pins being arranged in line and equally spaced, as best shown in Fig. 4, while the fifth pin is displaced from the line formed by the other

pins and is substantially equidistant from the center pins 5 and 7. The contact pins 4, 5, 6, 7 and 8 are so spaced as to coöperate with the contact members of a readily attachable and detachable receptacle or connector 9 which is provided with four contact openings containing contact members which are connected in pairs by means of conductors 10 and 11 leading to line conductors (not shown) connected to a source of current.

The heating device 1 is provided with two heating coils 12 and 13. As shown in Fig. 4, one terminal of the coil 12 is connected to the contact pin 6 by means of a conductor 14 which is also connected, by means of conductors 15 and 16, to the contact pins 4 and 8, respectively. One terminal of the coil 13 is connected to the contact pin 7 by means of a conductor 17, and the coils 12 and 13 are both connected, at 18, to a conductor 19 which is connected to the contact pin 5.

The method of obtaining high, medium and low heats by means of the above-described arrangement is best shown in Fig. 4. When low heat is desired, the receptacle 9 is attached to contact pins 7 and 8, the coils 12 and 13 being thereby connected in series relation. When medium heat is desired, the receptacle 9 is attached to contact pins 4 and 5, thereby connecting only the coil 12 in circuit. If high heat is desired, the coils 12 and 13 are connected in parallel-circuit relation by attaching the receptacle 9 to the central group of contact pins 5, 6 and 7.

My invention is not restricted to the specific form of electric current-consuming apparatus which I have herein shown for the purposes of illustration, and no other limitations are to be imposed upon my invention except such as are indicated in the appended claims.

I claim as my invention:

1. A terminal device for electric current-consuming apparatus comprising a plurality of contact members disposed in a line and equally spaced, another contact member displaced from the line of the said first-named contact members and disposed substantially equidistant from certain of the said contact members, and means adapted to coöperate with said contact members to connect them in selectively different combinations, said means comprising a contact re-

ceptacle that is positioned on said contact members in a plurality of alined positions.

2. A terminal device for electric-current-consuming apparatus comprising a plurality 5 of contact members adapted to coöperate in selectively different combinations with a contact receptacle having only four contact members electrically connected in pairs.

3. A terminal device for electric-current-consuming apparatus comprising a plurality 10 of contact members disposed in alinement and equally spaced, another contact member displaced from the line of the said first-named contact members and disposed substantially equidistant from certain of the 15 said contact members, and a receptacle having only four contact members electrically connected in pairs and adapted to connect the said contact members in selectively different combinations. 20

4. An electrical current-consuming device comprising two conductors adapted to be connected in series or parallel relation, a terminal device associated with the said conductors and comprising four alined and 25 equally spaced contact members and a fifth contact member disposed substantially equidistant from the two intermediate alined contact members, and means coöperating with said terminal device to selectively connect the contact members thereof in different 30 combinations, said means comprising a contact receptacle that is located on said contact members in a plurality of alined positions. 35

5. An electric current-consuming device comprising two conducting coils, a terminal device comprising four alined and equally spaced contact members, a fifth contact member disposed substantially equidistant from 40 the two intermediate alined contact members, and conductors connecting the last-named contact member with the two outer

alined contact members and with one terminal of one of the said coils, for connecting one terminal of the other coil with one of the intermediate alined contact members and for connecting the remaining terminals of both coils to the other intermediate alined contact member. 45

6. A terminal device for electric-current-consuming apparatus comprising a plurality of contact members adapted to coöperate in selectively different combinations with a contact receptacle, said contact members being 50 disposed in a manner to permit the contact receptacle to be located on said contact members in a plurality of alined positions. 55

7. A terminal device for electric-current-consuming apparatus comprising a plurality 60 of contact members adapted to coöperate in selectively different combinations with a contact receptacle, said contact members being disposed in alinement to permit the contact receptacle to be located on said contact members in a plurality of alined positions. 65

8. In an electric-current-consuming apparatus comprising two conducting coils, a terminal device comprising a plurality of contact members adapted to coöperate in selectively different combinations with a contact receptacle, said contact members being disposed in a manner to permit the contact receptacle to be located on said contact members in a plurality of alined positions, to 70 selectively connect the two conducting coils in three different combinations to electrically connect a source of current to only one conducting coil, to both coils in parallel, or to both coils in series to obtain three different 75 degrees of heat in said apparatus. 80

In testimony whereof, I have hereunto subscribed my name this 30th day of Oct. 1916.

FRANK THORNTON, JR.
